UNITED STATES PATENT OFFICE.

STEWART SHAFFER, OF IDAVILLE, INDIANA.

GASOLENE CUT-OFF FOR AUTOMOBILES.

1,130,027.

Specification of Letters Patent.

Patented Mar. 2, 1915.

Application filed April 4, 1914. Serial No. 829,717.

To all whom it may concern:

Be it known that I, STEWART SHAFFER, a citizen of the United States, residing at Idaville, in the county of White and State of

5 Indiana, have invented certain new and useful Improvements in Gasolene Cut-Offs for Automobiles, of which the following is a specification, reference being had to the accompanying drawings.

10 This invention relates to a gasoline cut-off for automobiles.

The object of the invention is to provide an article of this character which may readily be applied to the gasoline pipe of an 15 automobile at any part between the tank and the carburetor, the adoption of the device not requiring any change whatever in the structural arrangement of the automobile, and which in operation will be positive 20 in preventing the use of the automobile without the owner's knowledge and consent.

With the above and other objects in view, as will appear as the nature of the invention is better understood, the same consists, 25 generally stated, in a gasoline cut-off for automobiles, comprising a cylinder, which may be of any preferred contour in cross section, and which is designed to be secured to the gasoline supply pipe at any point between the tank and the carburetor. This cylinder houses a plunger which, in its lower position, positively cuts off passage through the gasoline supply pipe. Combined with the plunger is a novel mechanism for holding 30 the same elevated while the machine is in use, the means comprising a bolt rigid with the plunger and having pivotally connected with its upper end, as by a rule joined, a latch that is designed to be brought 35 into interlocked relation with a keeper depending from the cap or closure of the top of the cylinder. The latch is held in normally vertical position by means of leaf springs secured on opposite sides of the bolt 40 and vertically embracing the latch, the latter being designed to be turned upon its pivot by a key of a construction that will render it difficult to imitate or reproduce.

A further feature of the invention resides 45 in the means for preventing access to the interior for the purpose of unseating the plunger or valve, the same consisting of a screw cap threaded on the upper end of the cylinder and having two positively aligned screws 50 for securing it in position, one of the screws being concealed within the cylinder, and re-

movable only from the interior thereof by a special tool furnished with the outfit, so that in the event that a person succeeds in removing one of the screws the cap is still 60 as firmly held in position as at first owing to the concealed screw.

Further and more specific details of the construction will be hereinafter fully described and claimed.

In the accompanying drawings forming a part of this specification, and in which like characters of reference designate corresponding parts:

Figure 1 is a view in vertical section 70 through a gasoline cut off formed in accordance with my invention; Fig. 2 is a similar view taken at right angles to Fig. 1; Fig. 3 is a horizontal sectional view taken on the line 3—3 of Fig. 1.

The cylinder 1 may be made of any suitable material, such as heavy sheet metal, and may be either circular or rectangular in cross section, preferably the former. Adjacent to the lower ends of the cylinder and on opposite sides thereof enter the two sections 2 and 3 of the gasoline supply pipe, one branch leading to the tank and the other to the carburetor. Passage between these pipe sections is controlled by a plunger 4 75 that fits snugly within the cylinder and carries an upstanding bolt 5, the upper end of which has pivotally connected with it at 6 a latch 7. The upper end of the latch terminates in an arm or catch 8, and at a point 80 intermediate of the length of the latch and projecting in an opposite direction to the catch 8 is a pin 9. The latch is held in vertical yielding position by two leaf springs 85 secured on opposite sides of the bolt, and having their upper ends crotched partly to embrace the latch, so that while the latter will be free to swing upon the pivot 6 it will 90 normally be maintained in a vertical position.

The exterior of the upper end of the cylinder is threaded and is engaged by a cap 11 from which depends a keeper 12 that is designed to coact with the catch 8 to hold the plunger in raised position and thus permit free passage of gasoline through the pipe sections 2 and 3. In addition to the threaded connection between the cap and the cylinder, the former is additionally held in place by two screws 13 and 14, the screw 13 105 being removable from the exterior of the cap, while the screw 14 is only removable 110

from the interior of the cylinder, and is accomplished by first removing the screw 13 and then inserting a specially constructed screw driver to engage with the screw 14. 5 By this arrangement, a double locking of the cap to the cylinder is secured, and access to the latter is practically precluded.

Projecting inward from one side of the cylinder, and rigid therewith is a key guide 10 15 having an eye 16 to receive the stem 17 of a key and a slot 18 to receive the ward 19 of the key, the latter being provided with an all through orifice 20 designed to pass over the pin 9, the guide being arranged to register with a key-hole in the side of the cylinder.

From the foregoing it will be seen that when the key is inserted through the key hole and key guide and the orifice 20 brought 20 into engagement with the pin 9, that upon the key being turned, the latch 7 will be moved to one side against the resistance of one of the springs 10, and during this movement the plunger will be raised. As soon 25 as the catch 8 passes over the keeper 12, further turning of the key is rendered unnecessary, and the gasoline will now freely pass through the pipe sections 2 and 3. When the owner leaves the machine the key is 30 turned in the reverse direction, thereby moving the latch out of engagement with the keeper and permitting the plunger to resume its normal position, that is resting upon the bottom of the cylinder, thereby 35 cutting off the passage of the gasoline. When this is accomplished the owner removes the key, and may feel reasonably sure that his machine will not be unlawfully used.

40 From the foregoing description, it will be seen that although the improvements herein described are simple in character, they will be thoroughly efficient for the purpose designed and coact in the presentation of a 45 durable and highly advantageous form of gasoline cut-off.

Having thus described my invention, what I claim is:

1. A gasoline cut off for automobiles 50 comprising a casing provided at its lower end with oppositely disposed pipes, a plun-

ger arranged in the casing and operating normally to close passage through the pipes, a bolt carried by the upper end of the plunger, a spring pressed latch pivotally connected with the upper end of the bolt and carrying at its upper terminal an outstanding catch and at an intermediate point an outstanding pin, a cap secured to the casing, and a keeper depending from the cap and 60 arranged to be engaged by the catch. 55

2. A gasoline cut off for automobiles comprising a casing provided at its lower end with oppositely extending pipes, a plunger arranged in the casing and operating normally to cut off passage through the pipes, a bolt rigid with the upper side of the plunger, a latch pivotally connected with the upper end of the bolt and provided at its upper end with an outstanding catch and 70 intermediate of its ends with an outstanding pin, springs secured to opposite sides of the bolt and engaging the latch to hold it normally in a vertical position, a cap secured to the upper end of the casing, a keeper depending from the cap and arranged to be engaged by the catch, and a key having an orificed ward to engage the pin whereby to raise the plunger and to impart lateral movement to the latch to permit 80 the catch to be engaged with the keeper. 75

3. A gasoline cut off for automobiles comprising a casing provided in its lower portion with oppositely disposed pipes, a plunger arranged in the casing and operating normally to cut off passage through the pipes, a bolt rigid with the plunger, a pivoted spring pressed latch carried by the upper end of the bolt and provided with an outstanding catch and with a pin, a cap 90 closing the upper end of the casing, a keeper depending from the cap, a key guide projecting through the side of the casing and having its eye disposed opposite the pin, and a key having an orificed ward to engage 95 with the pin to raise the plunger. 85

In testimony whereof I hereunto affix my signature in the presence of two witnesses.

STEWART SHAFER.

Witnesses:

CLIFFORD SHAFER,
HARRY T. HODLOVE.
